UNITED STATES PATENT OFFICE.

LEONARD W. WALLACE, OF RICHMOND, VIRGINIA.

LADDER STRUCTURE.

1,189,514.

Specification of Letters Patent.

Patented July 4, 1916.

Application filed June 25, 1915. Serial No. 36,272.

To all whom it may concern:

Be it known that I, LEONARD W. WALLACE, a subject of the King of England, residing at Richmond, in the county of Henrico, State 5 of Virginia, have invented certain new and useful Improvements in Ladder Structures; and I do hereby declare the following to be a full, clear, and exact description of the invention, such as will enable others skilled 10 in the art to which it appertains to make and use the same.

This invention relates to new and useful improvements in ladder structures and has for its object the provision of a ladder for 15 use on inclined roofs or the like and which includes step portions which are angularly adjustable with relation to the body portion of the ladder so that they may be adjusted to lie in horizontal planes irrespective of the 20 relative slant of the surface on which the ladder is positioned whereby said step portions may serve as proper seats for buckets of paint or for tools and whereby the safety and the convenience of persons working on 25 the ladder is enhanced.

It is further an object to provide such an adjusting means for the steps of a ladder structure which may be readily and quickly operated to properly position the steps and 30 which comprises a structure of maximum simplicity and lightness consistent with strength and durability.

With the above and other objects and advantages in view, the invention resides more 35 particularly in the novel combination, formation and arrangement of parts as more fully described hereinafter and pointed out in the appended claims.

Reference is had to the accompanying 40 drawings, wherein similar characters of reference designate corresponding parts throughout the several views, and in which:

Figure 1 is a top plan view of a ladder structure constructed in accordance with the 45 present invention and comprising a plurality of connected ladder sections, Fig. 2 is a central longitudinal sectional view through one of the sections on the line 2—2 of Fig. 1, Fig. 3 is a transverse sectional view through 50 one of the sections on the line 3—3 of Fig. 2, Fig. 4 is an end edge view of one of the ladder sections, Fig. 5 is a perspective view of the bracket member for securing the steps

to the sides of the ladder, Fig. 6 is a view in plan showing a modified means of connecting the ladder sections.

Referring now more particularly to the accompanying drawings, there are shown a plurality of ladder sections A adapted to be secured on a roof or the like in standing relation, and each including side bars 5. The preferred means for connecting these ladder sections comprises rods 6 secured to the end of the side bars and extending outwardly thereof, the free ends of the rods carried by 65 one end of one section being bifurcated at 7 to receive the ends of the rods carried by the adjacent end of the other section, and secured as by the bolts 8.

Each of the sections 5 are secured together and held in spaced relation by bolts 9 and further by diagonal cross strips 10 at the end portions of their body edges. Each section is also provided with a series of step portions 11 which are angularly adjustable 75 so as to position them in the horizontal planes irrespective of the angularity of the roof on which the section is placed, and to accomplish this the steps are pivotally secured between the side bars 5 by angle plates 80 12 at their ends which are pivoted to bolts 13 extending through the side members, these pivotal connections of the plates being disposed adjacent the bottom edge portions of the sides 5. The inner faces of the sides 5 85 are provided adjacent their top edges with grooves 14 extending longitudinally throughout and slidably set in these grooves are bars 15 which carry at spaced intervals inwardly extending pins 16 slidably disposed in slots 90 17 in the plates 12, which extend transversely of the said bars 15 so that as the bars are moved the steps will be swung around the pivot bolts 13 for actuating these bars, adjacent ends thereof are reduced as at 18 and 95 passed through a transverse plate 19 secured across the adjacent ends of the side bars 5 and wing nuts 20 are threaded on said reduced ends 18 outwardly thereof. The bars are resiliently urged toward the other end 100 of the ladder section by springs 21 secured to the bars 5 and bearing against pins 22 projecting from the bars 15. Thus to adjust the steps, the nuts 20 are turned in either direction, or one of the steps may be 105 grasped and swung to its desired relative

position, thus swinging the other steps and the nuts may then be tightened to hold them in this desired position. The bars 15 are held in place by the angle plates 12 of 5 the steps, but a further means for holding said bars is provided comprising screws 23 which are passed through slots 24 in the bars 15 and engage the main bars 5.

Thus an exceedingly simple and compact 10 device has been provided which may be readily operated to position the steps thereof at any relative position. It is noted that the structure for turning the steps is sufficiently housed and held between the plates 12 and 15 the main side bars 5 so that the device is not liable to accidental injury.

In Fig. 6 is shown a slightly modified 20 form of connecting the sections A, which consists merely in securing them with their sides in lapped relation and passing bolts 25 through the engaging side bars. That ladder section which is used as the uppermost one has secured outwardly to its sides a pair of hooks 26 which are adapted to hook over 25 the upper edge of the roof to hold the ladder structure in place. To facilitate placing the ladders on the roof and moving them about their arm, wheels 27 may be secured on one of the side bars of the section, so that it may 30 be turned edge-wise and rolled into place.

While I have illustrated and described a particular embodiment of my invention, I have merely done so for the sake of convenience and I do not wish to be limited to 35 that particular embodiment as it is obvious that numerous changes may be made within the details of construction thereof without in any way departing from the spirit of the

invention or exceeding the scope of the appended claims.

40

What I claim is:—

1. In a ladder structure, the combination with parallel side bars, of a plurality of step sections carried therebetween, and means slidably mounted in the bars and having 45 slotted connections with the steps for adjusting and securing the latter in angular relation to the bar.

2. A ladder structure comprising the combination with a pair of side bars held in 50 spaced relation, of step sections, each including a lateral portion at each end pivoted to the side bars and provided with slots, the inner faces of the side bars being provided with longitudinal grooves, bars slidably held 55 in said grooves, pins on the bars extending into the slots and means for moving and holding the bars.

3. A ladder structure comprising side bars, steps disposed between the bars and having 60 lateral portions pivoted to the inner faces thereof and provided with slots, the said inner faces of the bars being provided with longitudinal grooves, strips in said grooves held by the lateral portions of the steps, 65 pins on the strips extending through the slots, means resiliently urging the strips in one direction and means adjustably holding said strips against movement in such direction.

In testimony whereof, I affix my signature, in the presence of two witnesses.

LEONARD W. WALLACE.
